UNITED STATES PATENT OFFICE.

HIRAM PERCY MAXIM, OF HARTFORD, CONNECTICUT, ASSIGNOR TO ELECTRIC VEHICLE COMPANY, OF HARTFORD, CONNECTICUT, A CORPORATION OF NEW JERSEY.

GEARING.

SPECIFICATION forming part of Letters Patent No. 764,896, dated July 12, 1904.

Original application filed June 3, 1896, Serial No. 594,058. Divided and application filed April 15, 1902, Serial No. 102,969.

Again divided and this application filed August 29, 1903. Serial No. 171,185. (No model.)

To all whom it may concern.:

Be it known that I, HIRAM PERCY MAXIM, a citizen of the United States, residing at 550 Prospect avenue, in the city of Hartford, State 5 of Connecticut, have invented certain new and useful Improvements in Gearing, of which the following is a specification, reference being had to the accompanying drawings, forming a part hereof, this application being a division of the application filed by me April 15, 1902, bearing the Serial No. 102,969, which was itself a division of the application filed by me June 3, 1896, Serial No. 594,058, forfeited, and renewed August 18, 1899, Serial 15 No. 727,703.

This invention relates in general to gearing, and more especially to the construction and operation of gearing for transmitting power and effecting changes of speed and direction.

The object of the invention is to provide an improved form of gearing and one which shall be so arranged and constructed that changes in the direction of the movement of 25 the vehicle, changes in the speed of the vehicle when moving in either direction, and the application of a brake can be controlled or effected by the movement of a single controller handle or lever.

In the application Serial No. 102,969, of 30 which this is a division, the features of improvement are set forth in their broader aspect, it being the intention in the present application to cover a particular embodiment 35 of the invention which in said former application is illustrated in different forms. The drawings of the present case, which are intended to illustrate the invention herein sought to be covered, show no more than is shown in 40 the drawings of said former application; but in order to avoid unnecessary repetition some of the figures of the present drawings are made to show features taken from other figures of the drawings of said former applica- 45 tion.

In the present drawings, Figure 1 is a view, partly in side elevation and partly in longi-

tudinal section, of a motor-vehicle to which the improved gearing is applied. Fig. 2 is a sectional view of the gearing shown in Fig. 50 1, the motor being also indicated, while the parts are represented as in relative positions which they do not assume in actual practice in order to avoid confusion in the drawings. Some parts of a vehicle and its running-gear 55 are also represented. Figs. 3 and 4 are respectively a side view and a diametrical section of one of the gears of the train represented in Figs. 1 and 2. Figs. 5 and 6 are similar views of another of the gears of said 60 train. Fig. 7 is a side view of one portion of the gearing shown in section in Fig. 2.

In order to enable the invention to be better understood, the gearing will be described with reference to its application in a motor- 65 vehicle. Such vehicle may be provided with a running-gear, comprising, as usual, side bars or reaches a and front and rear cross-bars a' , these bars being preferably tubular in construction. The rear cross-bar a' has depending arms or hangers a'' , which support the rear axle c^2 , and the front cross-bar a' furnishes support for the front axle b through any desired connection, not necessary to be specifically shown. Between the two side- 70 bars a extend ordinary carriage-springs a^4 , which support the carriage box or body x , and the carriage-springs a^5 , which support the motor-platform y . The latter is free from the former at all points, and the two are thus 75 supported independently of each other, whereby the vibrations of the motor are prevented from being transmitted to the carriage box or body and the motor is prevented from being affected in any manner by any movement 80 of the carriage box or body. The particular type of motor employed is not concerned in the present invention, and a detailed description thereof is therefore unnecessary. It is 85 obvious that a motor of any type—such as vapor, steam, or electric—might be employed. For illustration, there is shown a motor of a 90 well-known type of internal-combustion engine, the two motor-shafts c^3 of the duplex

motor being represented as coupled together by means of the common gear m . The latter meshes with the gear m' on the shaft m^2 , which is mounted to rotate in suitable bearings on the motor-platform. The gear m' is a common driving-gear for the two gears m^3 m^4 , which are mounted loosely on the shaft m^2 , one on each side of the gear m' , and are adapted to be coupled or clutched thereto at the will of the operator. The gear m' has on each side lugs m^5 , which are adapted to be engaged by corresponding lugs m^6 on an adjacent face of the gear m^3 or m^4 , and the latter are carried by and are free to rotate upon short sleeves m^7 , which are adapted to be moved longitudinally on the shaft m^2 by a double clutch-lever m^8 . The gears m^3 m^4 mesh, respectively, with the gears m^9 m^{10} , which are fast upon a driving-shaft m^{11} , the latter being free to rotate in suitable bearings carried by swinging arms m^{12} , which are hung upon the shaft m^2 . It is apparent that when either one of the gears m^3 m^4 is moved into engagement with the gear m' the shaft m^{11} will be driven at a corresponding speed and the other gear, m^4 or m^3 , will rotate idly upon its carrying-sleeve m^7 . From the shaft m^{11} motion is transmitted to the rear axle by gears presently to be described, and such gears are maintained in proper relation by links m^{13} , which connect the shaft m^{11} with the rear axle. It will be readily understood that as the motor-platform oscillates with respect to the running gear the gears carried by the shaft m^{11} , which is supported wholly by arms and links m^{12} m^{13} , will always maintain their engagement with the respective gears on shaft m^2 and the rear axle notwithstanding the changes of position of the former with respect to the latter. The gear which transmits motion from the shaft m^{11} to the rear axle comprises both the ahead-clutch and the backing-clutch, which are controlled by the operator by means of suitable intermediate mechanism. The construction of this gear is preferably as follows: The gear-teeth are formed upon a ring n , which is carried by a shell mounted loosely upon the shaft m^{11} . As represented, the said shell is formed in two parts n' n^2 , which are rigidly united by the ring n . The shell n' carries an internal gear n^3 , which is engaged by pinions n^5 , mounted on studs n^7 , carried by a shell or friction-drum n^9 , the latter being mounted loosely on the shaft m^{11} . A pinion n^{11} is secured to the shaft m^{11} to rotate therewith and engages the pinions n^5 . The shell n^2 is provided with studs n^4 , upon which are mounted pinions n^6 , which mesh with an internal gear n^8 , carried by a shell or friction-drum n^{10} , the latter being mounted loosely on the shaft m^{11} . A pinion n^{12} is fixed upon the shaft m^{11} to rotate therewith and engages the pinions n^6 . It is apparent that whenever both drums n^9 n^{10} are free to rotate no motion will be imparted from the shaft m^{11} to the gear n ,

the pinions n^5 in one case revolving freely about the shaft as they rotate upon their own axes without moving the internal gear n' and the pinions n^6 in the other case causing the internal gear n^8 to rotate, and hence failing to revolve about the shaft m^{11} , and therefore failing to rotate the shell n^2 and the gear n . However, if the rotation of either shell n^9 or n^{10} is retarded motion will be imparted to the gear n in one direction or the other, the maximum speed of said gear n being attained when one shell, n^9 , or the other, n^{10} , is held stationary.

It is apparent that if suitable means are provided for retarding the rotation of the shells n^9 or n^{10} the speed of the vehicle can be graduated by the operator exactly as he desires up to the maximum determined by the speed of the driving-shaft m^{11} and the direction of movement of the vehicle, whether forward or backward, be determined also while the maximum speed of the shaft m^{11} , and hence of the vehicle, may be varied as above, according to the requirements of its use, by regulating the governor of the motor. The gears m^3 m^4 are shifted into or out of engagement with the driving-gear m' , according to the amount of load carried by the vehicle and the character of the road upon which it travels. The gear n meshes directly with the gear o on the rear axle, this gear being preferably a balance-gear such as that already referred to in order to allow independence of movement of the two rear wheels.

A suitable friction-strap p may be provided to regulate the rotation of each shell or friction-drum n' n^2 , and it may be placed under the control of the operator by suitable intermediate devices.

Letter p represents one friction-strap, connected by a link p' with a bell-crank lever p^2 , arranged to be operated by the cam p^3 on a shaft p^4 , to which movement may be imparted by any suitable means—such, for example, as the controller-lever, link, gear, segment, and pinion on the shaft. Similarly the other friction-strap, p , may be operated through a bell-crank lever p^5 , link p^6 , and bell-crank lever p^7 from a cam p^8 on the shaft p^4 , the cams p^3 p^8 being so disposed relatively to each other as to tighten but one strap at a time, leaving the other loose, while they have a common neutral point which will permit both straps to be loosened at the same time in order to bring the vehicle to a stop. The clutch-lever m^8 may also be operated by any suitable means under control of the operator, and a convenient arrangement for this purpose consists of a link q and a spring q^2 to maintain the small gear m^4 normally in engagement with the gear m' and the bell-crank lever q^2 , arranged to be operated by the foot of the operator through a suitable bolt q^3 .

It will be evident that the action of the controller-handle, f^9 , through the intermediate

connections and the friction-straps or brake-bands p , upon the shells or drums of the respective ahead and backing gears not only controls the direction of movement of the vehicle, but also controls the application of a brake to a vehicle when the same is moving in either direction. Thus if the vehicle is going ahead with the controller-handle in its forward position the movement of the controller-handle to its middle position will leave both the ahead-gearing and the backing-gearing free, permitting the vehicle to coast. If now while the vehicle is still moving ahead the controller-handle be moved back of its middle position, it will, through the action of the friction strap or brake upon the shell or drum of the backing mechanism, which shell or drum is of course rotating ahead, at first apply a brake to the vehicle through such shell or drum. The continued application of the brake to the shell or drum will eventually result in such retardation thereof as to cause the backing mechanism to act and the vehicle to be propelled backward. The single controlling-handle has, therefore, the functions of a brake-handle as well as the functions of a reversing-lever. It will be further observed that as the ahead mechanism, as well as the backing mechanism, is also a speed-changing mechanism, as determined by the slip of the shell or drum, the same controller-handle f^9 is adapted not only to control the speed of the driving mechanism, but to apply a brake to the vehicle as well under such conditions as have been described above.

The mode of operation of the several features of the improvement has been sufficiently set forth in the above description, and no further explanation thereof or of the application thereof to a vehicle need be given.

It is obvious that many changes can be made as to the construction of the gearing and the arrangement thereof in a vehicle, and it is understood, of course, that the uses of the gearing are not confined to a vehicle and that such gearing might be employed in connection with any device in which it is desirable to effect changes of speed and the direction of movement of a given shaft.

What I claim, and desire to secure by Letters Patent, is—

1. In a motor-vehicle, the combination with a driving-shaft m^{11} , means to actuate said driving-shaft and a driven gear o of a gear n mounted to rotate freely upon said shaft and meshing with said driven gear o , an internal gear n^3 carried with said gear n , a shell or drum n^9 mounted to rotate freely upon said shaft, a pinion n^5 carried by said shell or drum to revolve about said shaft, a driving-pinion n^{11} fixed to said shaft and engaging said first-named pinion, and means to retard the rotation of said shell or drum.

2. In a motor-vehicle, the combination with a driving-shaft m^{11} , a gear n mounted to rotate

freely on said shaft, and a driven gear o , of an internal gear n^3 carried with said gear n , a shell or drum n^9 mounted to rotate freely upon said shaft, a pinion n^5 carried by said shell or drum and engaging said internal gear n^3 , a driving-pinion n^{11} fixed upon said shaft and engaging said first-mentioned pinion, a pinion n^6 carried with said first-named gear to revolve about said shaft, a second pinion n^{12} fixed to said shaft and engaging said last-named pinion, a second shell or drum n^{10} , carrying an internal gear to mesh with said last-named pinion, and means to retard the rotation of either of said shells or drums.

3. In a driving apparatus, a shaft, two main members loose on said shaft, an auxiliary member also loose on said shaft, and two independent power-transmitting mechanisms each including three elements, the three elements of one power-transmitting mechanism being carried respectively by said shaft, a main member and the auxiliary member, and the three elements of the other power-transmitting mechanism being carried respectively by the shaft, said auxiliary member and the other main member, and the first elements of each power-transmitting mechanism being fixed to said shaft and the intermediate ones being rotative upon their supports.

4. In a driving apparatus, a shaft, two main members loose on said shaft, an auxiliary member also loose on said shaft, two independent power-transmitting mechanisms each including three elements, the three elements of one power-transmitting mechanism being carried respectively by said shaft, a main member and the auxiliary member, and the three elements of the other power-transmitting mechanism being carried respectively by the shaft, said auxiliary member and the other main member, and the first elements of each power-transmitting mechanism being fixed to said shaft and the intermediate ones being rotative upon their supports, and means for alternately limiting the motion of the main members.

5. In a driving apparatus, a shaft, two main members loose on said shaft, an auxiliary member also loose on said shaft, two independent power-transmitting mechanisms each including three elements, the three elements of one power-transmitting mechanism being carried respectively by said shaft, a main member and the auxiliary member, and the three elements of the other power-transmitting mechanism being carried respectively by the shaft, said auxiliary member and the other main member, and the first elements of each power-transmitting mechanism being fixed to said shaft and the intermediate ones being rotative upon their supports two band-brakes located to peripherally engage said main members and means for alternately operating said band-brakes.

6. In a driving apparatus, a shaft, two main

members loose thereon, an auxiliary member loosely supported upon the shaft between said main members, and two independent trains of intermeshing gears, the first members of each 5 of said trains being keyed to the shaft and the other members of said trains being carried respectively by said auxiliary member and the main members.

7. In a driving apparatus, a shaft, two main 10 members loose thereon and one of them having an annular gear device, an intermediate member also loose upon said shaft and provided with an annular gear device, two gears meshing respectively with said annular gear device, 15 one of them being rotatively carried by said intermediate member, the other one being rotatively carried by one of the main members, and gears meshing with said rotatively-carried gears and fixed to said shaft.

20 8. In a driving apparatus, a shaft, two main members loose thereon, one of said members being provided with an inturned annular flange, provided upon its inside face with an annular gear device, a member intermediate said main 25 members and also loose upon said shaft and provided with an outwardly-disposed flange having an annular gear device upon its inner face, two gears rotatively carried respectively

by the intermediate member and by one of the main members and meshing with said annular gear device, and gears fixed to the shaft and meshing with said rotatively-carried gears. 30

9. In a motor-vehicle, the combination with a driving-shaft n^{11} , a gear n mounted to rotate freely on said shaft, and a driven gear o , of an internal gear n^3 carried with said gear n , a shell or drum n^9 mounted to rotate freely upon said shaft, a pinion n^5 carried by said shell or drum and engaging said internal gear n^3 , a driving-pinion n^{11} fixed upon said shaft and engaging said first-mentioned pinion, a pinion n^6 carried with said first-named gear to revolve about said shaft, a second pinion n^{12} fixed to said shaft and engaging said last-named pinion, a second shell or drum n^{10} , carrying an internal gear to mesh with said pinion n^6 , and means coöperating with the gear n and with the main shaft for effecting the reversed motion of the driven gear o . 35 40 45 50

This specification signed and witnessed this 27th day of August, A. D. 1903.

HIRAM PERCY MAXIM.

In presence of—

CHARLES G. HUNTINGTON,
RUDOLPH RIEGE.
